(57) **CLAIM**

The ornamental design for an USB memory stick, as shown and described.

DESCRIPTION

FIG. 1 is a perspective view of a USB memory stick showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a perspective view thereof, shown in the context of a different unclaimed portion.

The broken line showings of the connector in FIGS. 1-7 and the connector in FIG. 8 are for the purpose of illustrating unclaimed portions of the USB memory stick and form no part of the claimed design.

The drafting break lines shown on the connector in the drawings represent that the connector is of non-specified length.
